UNITED STATES PATENT OFFICE.

FREDERICK WILLIAM BOCKING, OF VAN BUREN, ARKANSAS.

RABBLE AND CLINKER-BREAKER.

1,308,653.

Specification of Letters Patent.

Patented July 1, 1919.

Application filed March 28, 1918. Serial No. 225,206.

To all whom it may concern:

Be it known that I, FREDERICK W. BOCKING, a citizen of the United States, residing at Van Buren, in the county of Crawford 5 and State of Arkansas, have invented a new and Improved Rabble and Clinker-Breaker, of which the following is a full, clear, and exact description.

My invention relates to a rabble and 10 clinker breaker particularly suitable for zinc furnaces. An object of the invention is to provide an apparatus of the class described which is simple in construction and by means of which the grate of the furnace 15 can be maintained clean of clinkers and, in consequence, a more even feed of the charge of ore through the furnace obtained.

With the above and other objects in view, the nature of which will more fully 20 appear as the description proceeds, the invention consists in the novel construction, combination and arrangement of parts as herein fully described, illustrated and claimed.

25 In the accompanying drawings, forming part of the application, similar characters of reference indicate corresponding parts in all the views.

Figure 1 is a longitudinal diagrammatic 30 section through a zinc oxid furnace equipped with apparatus embodying my invention;

Fig. 2 is an enlarged longitudinal section through the furnace and through the rab- 35 ble and clinker breaker on line 2—2, Fig. 4;

Fig. 3 is a horizontal section on line 3—3, Fig. 2;

Fig. 4 is a cross section on line 4—4, Fig. 2;

40 Fig. 5 is a vertical section on line 5—5, Fig. 2;

Fig. 6 is a horizontal section on line 6—6, Fig. 2; and

45 Fig. 7 is a vertical section on line 7—7, Fig. 2.

When a charge of zinc-bearing material mixed with a reducing agent is put on what is known as the Wetherell grate and heated, the material forms more or less of a clinker, 50 and on account of this formation it is im- possible to move the material mechanically through a zinc oxid furnace during the process of treatment. The method of han- 55 dling the charge in such cases would be to discharge the treated material out of one end as fast as fresh charge was put in at the

other end. On account of the clinkers, the rabbles, when engaging such clinkers, have a tendency to move the entire charge ahead before the charge has been thoroughly 60 treated, or, in other words, the rabbles would push the entire charge out of the furnace at the first engagement with it, instead of pushing or rabbling the charge through in several interrupted stages and, 65 in consequence, giving time to the charge to be properly treated.

To overcome this deficiency in the present method of treating zinc ores, the charge is allowed to remain dormant in the furnace 70 until the treatment is completed. In many instances a portion of the charge is treated before the remainder. In consequence, there is a loss of time due to the double treatment of a single charge. After the 75 charge has been converted the clinkers are broken up with iron bars and raked out by hand, and another charge is then put in. It will be noted that during the time of clean- 80 ing out the clinkers and putting in a fresh charge a great deal of time is lost, besides the amount of hard labor required to remove the clinkers.

To obviate the defects pointed out above, I provide a combined rabble and clinker 85 breaker which is adapted to automatically clean a Wetherell grate, thereby allowing a continuous operation of the furnace. To this end I provide a carriage which has a frame 9, preferably built of structural iron. 90 An axle 10 is provided near one end of the frame, and it carries a row of star wheels 11 each revolubly mounted on the axle. Each of said wheels has a plurality of spokes 12 which, in turn, will break up the clinkers 95 formed in the charge of the ore in the fur- nace. It will be noted that each wheel re- volves independently of the other, and to obtain a better breaking up of the clinkers the end of each spoke is tapered to an edge, so 100 that under the weight of the carriage the edge will have a tendency to cut through the material and, therefore, break up the clinkers formed therein. The adjacent spokes have their tapered edges at right 105 angles to one another. With soft ores the rear of the carriage may be provided with ordinary wheels 13 which, in consequence, will form a rolling support for the carriage in the rear.

110 Positioned between the wheels 11 and 13 are the rabbles 14 disposed in two parallel

sets in staggered relation so that the rabbles of the two sets will comb the surface of the grate as the carriage is moved through the furnace. Each set of rabbles is secured to a 5 corresponding bar 15 which are mounted to turn in the frame 9 of the carriage. The sets of rabbles being bottom heavy, normally tend to remain in vertical position, as shown in Fig. 2. To prevent the swinging 10 of the bars when the rabbles plow through the charge on the grate, stops 16 are provided, which are in the shape of rolls, on a frame 17 which is movable relative to the carriage frame 9. The stops 16 lie in the path of the extreme rabbles of the 15 sets, and when the said rabbles engage said stops the bars 15 are prevented from moving in the carriage frame.

The frame 17 rests on rollers 18 which are 20 allowed to float on the carriage frame 9, the floating motion of the rollers being limited by brackets 19 secured to the frame 17. The movement of the frame 17 on the carriage frame 9 is positively limited by stops 20 provided at the ends of the frame 17. By moving the frame 17 to the rear of the frame 9, the rabbles are thrown at an angle, best 25 shown in Fig. 1. In such positions of the rabbles the carriage can be drawn to the 30 charge end of the furnace without dragging out the charge on the grate. The movement of the carriage is controlled by a flexible member 21 mounted on suitable drums 22, and which flexible members are connected to 35 the frame 17. The frame 17 is prevented from rising off the carriage frame 9 by members 23.

In the position shown in Fig. 1 the rabbles and clinker breaker is at the charge end of 40 the furnace. The frame 17 is shown with a cam 24 located near the forward end of said frame, which cam is shown in operative engagement with the ore-discharge control 25. In other words, when the cam has engaged 45 the discharge control 25, a certain amount of ore is charged from the trough 26 into the furnace 27. The cable 21 to the right of the furnace is then wound on its drum 22. The winding of the cable will first move the 50 frame 17 on the carriage frame 9. In consequence, there is an initial displacement of the frame 17 relative to the carriage frame 9 which causes the rabbles to move to the vertical position, as shown in Fig. 2.

55 The further winding of the cable will entrain the carriage into the furnace and the spokes or arms 12 will be caused to travel through the charge on the grate 28 of the furnace and break up any clinkers that may 60 have formed. As the carriage progresses, the rabbles begin to plow the charge and,

therefore, replace the treated charge in the furnace by the freshly discharged load to be moved or advanced into the furnace. In view of the fact that the rabbles are preceded by the clinker breaker, there is no danger of the rabbles causing a bodily discharge of the entire load of the furnace out before the same is properly treated. 65

After the carriage has been moved through the furnace it is dragged by turning the drum to the left. The winding of the drum will first cause a movement of the frame 17 on the carriage frame 9, thereby permitting the rabbles to swing to a point so as not to 70 move the charge rearwardly. When the carriage is brought to the front and a new charge of ore is made, the cycle is repeated. 75

I claim:

1. In a rabbles and clinker breaker, a carriage, series of rabbles on the carriage, each series being mounted to swing in an axis transverse of the carriage, and means having a limited sliding movement on the carriage in direction of movement of the carriage and 80 including means for engaging the rabbles, whereby said rabbles may be placed into operative or into inoperative position.

2. In a rabbles and clinker breaker, a carriage, a series of rabbles on the carriage, 90 each series being mounted to swing, a frame having a limited movement on the carriage, means for propelling the carriage secured to the frame, and means carried by said frame for engaging the rabbles, whereby said rabbles may be maintained in operative or in 95 inoperative position.

3. In a rabbles and clinker breaker, a carriage, series of swinging rabbles on the carriage, a frame on the carriage and movable 100 relative thereto, and means for propelling the carriage attached to the frame whereby said frame has an initial displacement relative to the carriage, said frame having means for engaging the series of rabbles whereby 105 said rabbles are swung substantially as and for the purpose set forth.

4. In a rabbles and clinker breaker, a carriage, series of swinging rabbles on the carriage, a frame on the carriage having stops 110 controlling the swinging movement of the rabbles, rollers interposed between the frame and the carriage, means limiting the rolling movement of the carriage on the frame, and means for propelling the carriage connected 115 to the frame.

5. In a rabbles and clinker breaker, a revolute star wheel the adjacent spokes of which have tapered edges at right angles to one another.

FREDERICK WILLIAM BOCKING.
